Primary Examiner — Samantha Wood(74) *Attorney, Agent, or Firm* — Tyler A. Stevenson;
Anna-lisa L. Gallo(57) **CLAIM**

I claim the ornamental design for a faucet, as shown and described.

DESCRIPTION

FIG. 1 is a front, top, right side perspective view of a faucet showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines of the disclosure represent portions of the faucet that form no part of the claimed design.
